COIL

Filed Dec. 17, 1924

UNITED STATES PATENT OFFICE.

HARRY C. NIGHTINGALE AND HAROLD C. NIGHTINGALE, OF PATERSON, NEW JERSEY.

COIL.

Application filed December 17, 1924. Serial No. 756,476.

In certain electrical appliances, as for tuning coils in radio installations, it is the object to provide a helical coil whose use will involve as little as possible loss of energy due to presence of a dielectric in its construction and the convolutions of whose coil proper or helix shall at the same time be as firmly as possible fixed each in a definite position, that is to say, laterally, transversely of the axis of the coil (whether bodily or radially), and circumferentially since it is known that the slightest displacement of any convolution out of its predetermined position relatively to the others seriously affects the efficiency of the coil. The coil hereinafter described and shown in the accompanying drawing very perfectly accomplishes this purpose and affords a construction which is also simple and inexpensive to manufacture and possesses certain other advantages which will be hereinafter pointed out or apparent to those skilled in the art.

In the drawing, Fig. 1 is an end elevation of one form of the coil;

Fig. 2 is a plan, with a part of the coil proper broken away on line 2—2, Fig. 1;

Fig. 3 is an end elevation of another form;

Fig. 4 is a section on line 4—4, Fig. 3;

Fig. 5 is a section on line 5—5 of Fig. 3;

Fig. 6 shows still another form in which a plurality of coils are supported one within another; and

Fig. 7 is a section of a fragment of the form shown in Fig. 6 on line 7—7 in that figure.

In Figs. 1 to 5 let *a* designate the coil proper or helix, which is here shown formed of wire.

In Figs. 1 and 2 clamping members *b* and *c* are arranged one inside and the other outside of the coil proper or helix and, extending longitudinally thereof so as to traverse its convolutions, coact to hold its convolutions especially in view of the following: One of the members, which are of dielectric material (say fibre), as *b*, has a series of transverse grooves *b'* in which the respective convolutions seat, and the other member *c* bears with pressure on the convolutions and coacts with the member *b* to exert a frictional hold on them; the wire is a trifle thicker than the recess formed by each groove is wide, so that it requires some force

to enter it and the resulting friction becomes a useful factor in the gripping coaction of the members. The convolutions are formed and assembled with the member *b* by placing the latter on a suitable cylindrical mandrel and then winding the wire to form the coil proper around the mandrel and member *b*, and so that the wire is forced into a groove on each turn. The two members may be held in the clamping relation to the convolutions by screw-bolts *d* which with their nuts *e* act to bind the members together and are preferably arranged at portions of the members which are shown protruding from the ends of the coil proper or helix. The two members *b* *c* not only clamp the coil proper but afford a mount therefor as shown in Fig. 1, where *f* is a panel to which the mount is secured by the screws and their nuts; *g* designates binding nuts for clamping the conducting wires *A* to the screws which thus affords binding posts both for wires *A* and the ends of the coil (see Fig. 4). The mere pressure, taken with the grooving of one of the members, is broadly within the scope of this invention; but we prefer to embody in the actual structure the detail now to be described, since it not only facilitates assembling the parts with the convolutions in the precise arrangement predetermined but positively insures against their individual creeping or other displacement relatively to the clamping members in the direction of the length of the wire: The convolutions have in alignment with each other longitudinally of the coil portions *a'* (dotted lines, Fig. 2, and see also Fig. 4) each arranged obliquely to the corresponding convolution; the grooves in member *b*, which receive these portions, are arranged correspondingly obliquely. In consequence of this construction, which broadly contemplates offsetting the portions of the convolutions which flank the member *c* relatively to the portions directly traversed by it, the coil proper or helix cannot move bodily in the direction of the length of the convolutions, or circumferentially thereof; in fact, each convolution is held against such movement and in each direction. This not only determines the relative positions of the convolutions to a nicety but very materially increases the stability of the coil as a whole.

Figs. 3, 4 and 5 show a construction following that of Figs. 1 and 2 except that

there are a plurality of sets of the clamping members, the supplemental set *h i* being removed circumferentially of the coil proper from the members *b c*; their screw bolts and nuts are indicated at *j*.

If the coil proper is thus held, as by the members *h i*, at a point removed from other clamping members, as *b c*, the convolutions become proof against displacement in every way. So far as we know it is new to provide a coil structure including a substantially helical coil proper and a plurality of means to clamp convolutions of such coil proper which are removed from each other circumferentially of the coil proper and unconnected with each other, whereby each convolution affected is not only definitely spaced at one point from its neighbors, and also held against shifting circumferentially, but is held at a remote point from distortion, bending or warping (as under temperature influence) laterally, the prevention of even almost microscopic displacement of the convolutions of a coil proper for tuning purposes in a radio apparatus being very necessary to the proper operation of the coil.

In Figs. 6 and 7 is shown a construction in which one or more laminated sets *h* of clamping members (two or more such members to a set) clamp a plurality of coils proper or helices alternating therewith—two such sets, remote from each other, being shown. In this case one of the end clamping members, as *h'*, may be plain or ungrooved and the others grooved at their corresponding faces, so that the back or ungrooved side of one member will coat with the grooved side of an adjoining member to clamp or grip the convolutions. In any so-called "low-loss" tuning coil of bare wire (illustrated in all the views of the accompanying drawing) heretofore devised the construction was not adapted so far as we are aware for the placement of coils proper in a concentric or nested arrangement. By resort to laminated clamping members alternated with the coils proper (of different diameters and arranged one within another) we are able to produce a coil having its convolutions in this arrangement.

In the construction of Figs. 6 and 7 we actually show two coils proper, primary *l* and secondary *m*, the latter comprising here three concentric convolution-groups ar-

ranged around the primary (*l*) and formed of a single wire as indicated by the connecting portions thereof at *m'*; the primary is here shown as having the lower two binding posts for its terminals and the secondary as having the upper two for its terminals, as indicated at *l² m²*, Fig. 7.

In any type of so-called "low-loss" coil of which we are aware the points and areas of contact of the dielectric medium for maintaining the coil proper in shape, as well as the mass or bulk of such medium, are not only greater than in our coil but the same invariably requires the use of some cementing medium, as shellac, which in our invention is entirely avoided and in fact unnecessary.

Having thus fully described our invention, what we claim and desire to secure by Letters Patent is:

1. A coil structure including a substantially helical coil proper and means to hold convolutions of the coil proper spaced from each other, each such convolution having an offset portion flanking said means and coactive therewith to prevent circumferential movement of the convolution in each direction.

2. A coil structure including a substantially helical coil proper and means to hold convolutions of the coil proper spaced from each other, each such convolution having an offset on each side of said means and coactive therewith to prevent circumferential movement of the convolution.

3. A coil structure including a substantially helical coil proper and means to hold convolutions of the coil proper spaced from each other, said means having a plurality of recesses receiving the respective convolutions and each such convolution having the portion thereof received by the corresponding recess arranged obliquely with respect to the remainder of the convolution.

4. A coil structure including a substantially helical coil proper and means to hold convolutions of the coil proper spaced from each other, each such convolution having an offset portion flanking said means and holding the convolution against circumferential displacement in each direction.

In testimony whereof we affix our signatures.

HARRY C. NIGHTINGALE.
HAROLD C. NIGHTINGALE.
